UNITED STATES PATENT OFFICE.

ROBERT E. WYLLIE AND JOHN D. TWOHIG, OF AMARILLO, TEXAS.

VALVE-SETTING MACHINE.

No. 894,995.

Specification of Letters Patent.

Patented Aug. 4, 1908.

Application filed October 12, 1907. Serial No. 397,161.

To all whom it may concern:

Be it known that we, ROBERT E. WYLLIE and JOHN D. TWOHIG, citizens of the United States, residing at Amarillo, in the county of Potter and State of Texas, have invented certain new and useful Improvements in Valve-Setting Machines, of which the following is a specification.

Our invention relates to new and useful improvements in valve setting machines and more particularly to a machine for revolving the main driving wheel of a locomotive to set the valves.

It is necessary to set the valves on a locomotive in order that the steam from the boiler to the cylinders may be equally distributed. The valves must be so positioned that when the crank pins of the driving wheels are on the dead centers, with relation to the pistons, the latter must necessarily be at one end of their stroke. When the eccentrics or other parts of the driving mechanism are disconnected from the driving wheels, as where the wheels are removed to turn down the tires or other repairs, it is necessary to revolve the wheels to properly connect the parts. This has usually been done by means of "pinch" bars, which not only requires the services of several men but is extremely laborious and slow.

It is therefore the object of our invention to provide a machine for revolving the main driving wheel which can be operated by one man with increased rapidity, so as to save not only time, labor and expense, but to more perfectly set the valves.

Finally the object of the invention is to provide a device of the character described that will be strong, durable and efficient, simple and comparatively inexpensive, to construct and one in which the several parts will not be liable to get out of working order.

With the above and other objects in view, the invention has particular relation to certain novel features, an example of which is described in the specification and illustrated in the accompanying drawings, wherein:

Figure 1 is a partial transverse vertical sectional view of an engine pit showing our machine in elevation, also the lower portion of the driving wheels in position on the machine, Fig. 2 is an end elevation of the machine showing a portion of one of the driving wheels resting thereon, and Fig. 3 is a vertical sectional view taken on the line x—x of Fig. 1,

looking in the direction of the arrow and showing some of the parts in elevation.

In the drawings the numeral 1 designates the side walls of the engine pit and 2 the rails which are set back from the inner edges of 60 said walls as shown in Fig. 1.

3 indicates the main driving wheel and 4 the axle. The engine or locomotive is raised so as to raise the wheels 3 above the rails 2.

The machine for revolving the wheels comprises a horizontal shaft 5 extending across the pit and having fixed on its extreme ends grooved rollers 6, shaped to receive the flanges 7 of the drive wheels, and fit the contour of the same. Thus when the shaft 5 and rollers 6 are revolved, the wheels 3 will be consequently revolved and properly positioned to set the valves of the locomotive. The shaft 5 is supported in bearings 8 disposed adjacent to the inner sides of the rollers 6. These 65 bearings are provided at their lower sides with laterally extending ears 9 receiving set screws 10 which bear on the top of the walls 1 near the inner edges thereof. By adjusting these set screws the machine is raised and lowered so as to throw the rollers 6 into and out of contact with the flanges 7, and it is apparent that by tightening these screws the pressure of the rollers 6 against the flanges 7 70 may be increased so that slipping or lost motion is obviated. For revolving the shaft 5 a gear 11 is keyed thereon adjacent one of the bearings 8. For driving this gear a hanger bracket 12 is secured to the inner side of said bearing and projects some distance below the 75 gear 11. This bracket supports a short drive shaft 14 projecting therebeyond and having a pinion 15 disposed within the bracket and meshing with the gear 11. The end of the shaft 14 which projects into the pit is suitably shaped or reduced for connection 80 with a suitable motor by which the shaft is driven and motion thus imparted to the machine.

It is to be understood that the shaft 5 and its revolving mechanism may be driven in either direction thus permitting a minute adjustment of the valves, driving wheels and other parts. When the work has been finished the machine may be readily removed by turning the set screws 10 to lower the 85 bearings 8 and disconnecting the shaft 14 with the motor.

It sometimes happens that in stopping the motor the parts are not brought exactly to the proper point, however this can be accom- 90

plished by applying a suitable tool to the end shaft 14 and turning the parts by hand until the desired point is reached.

What we claim, is:

- 5 1. In a locomotive valve setting machine, a shaft, rollers adapted to engage the driving wheels of a locomotive mounted on the shaft, bearings supporting said shaft, means for vertically adjusting the bearings, and means for transmitting motion to the shaft.
- 10 2. In a locomotive valve setting machine, a shaft, rollers adapted to engage the driving wheels of a locomotive mounted on the shaft, bearings supporting said shaft, means for vertically adjusting the bearings, a gear carried by the shaft, a drive shaft supported adjacent the gear, and a pinion meshing with the gear mounted on the drive shaft.
- 15 3. In a locomotive valve setting machine, a shaft, rollers mounted on the shaft, means for adjusting the shaft vertically, and means for transmitting motion to the shaft.
- 20 4. In a locomotive valve setting machine, a shaft, grooved rollers mounted on the shaft adapted to receive the flanges of locomotive wheels, and means for transmitting motion to the shaft and rollers.
- 25 5. In a locomotive valve setting machine, a shaft, bearings supporting the shaft, rollers

adapted to receive the wheels of a locomotive 30 mounted on the shaft, a gear mounted on the shaft, a pinion supported in mesh with the gear, and means for imparting motion to the pinion.

6. In a locomotive valve setting machine, 35 a shaft, bearings supporting the shaft, rollers adapted to receive the wheels of a locomotive mounted on the shaft, a gear mounted on the shaft, a hanger carried by one of the bearings, a shaft mounted in the hanger, and a 40 pinion mounted on the shaft meshing with the gear.

7. In a locomotive valve setting machine, 45 a shaft, rollers adapted to engage the wheels of a locomotive mounted on the shaft, means for transmitting motion to the shaft, and a shaft associated with said transmitting means having a reduced end to receive a hand operating tool.

In testimony whereof we have signed our 50 names to this specification in the presence of two subscribing witnesses.

ROBERT E. WYLLIE.
JOHN D. TWOHIG.
